UNITED STATES PATENT OFFICE.

BERT E. BARTHOLOMEW, OF PASADENA, CALIFORNIA, ASSIGNOR TO SANDS PRODUCTION COMPANY, OF CLEVELAND, OHIO, A CORPORATION OF OHIO.

FRENCH WINDOW AND DOOR CASEMENT FASTENER.

Application filed March 16, 1927. Serial No. 175,737.

This invention relates to cupboard catches, and it is an object of the same to provide a catch that is adapted to fit all manner of small cupboards such as kitchen cupboards, 5 medicine-cabinets and the like.

A still further object of my invention is to provide a cupboard catch that may readily be locked in position and maintain itself in this position.

10 Another object of this invention is to provide a cupboard catch that is simple in its construction, contains relatively few moving parts, is unlikely to get out of order, and is well adapted to perform the services 15 required of the same.

With the foregoing and other objects in view which will be made manifest in the following detailed description and specifically pointed out in the appended claims, reference is had to the accompanying drawings 20 for an illustrative embodiment of the invention, wherein:

Figure 1 is a front view of my cupboard catch showing the same applied to a cupboard door.

Figure 2 is a sectional view taken along the lines 2—2 of Figure 1.

Figure 3 is a sectional view taken along the lines 3—3 of Figure 2.

30 In the above drawings like characters of reference designate like parts throughout, and the reference numeral 1 designates a cupboard door, and the numeral 2 designates the jamb. The jamb is provided with a socket member 3 held in place by the small wood screw 4, and this socket is adapted to receive the bolt on my improved cupboard catch. My cupboard catch is adapted to be embedded in the cupboard door in a suitable 40 space provided for the same. This catch comprises a substantially rectangular container having top and bottom walls 5 and 6, rear walls 7, side walls 8 and 9, and a front wall or plate 10, which is fastened to the cupboard by means of wood screws 11. The front wall 10 is provided as at 12 with an aperture, defined by a pair of inwardly 45 extending flanges 13 and 14. These flanges form a sliding journal for a bolt 15. The bolt 15 is threaded at one end as at 16 and is receivable in a sliding member 17, or follower, which member is rectangular in shape and has therethrough a substantially elliptical aperture 18. The side walls 8 and 9 55 are apertured at 19 and 20, which apertures

19 and 20 are directly opposed on the side walls, and mounted in these apertures is a cylindrical piece 21 to which is keyed eccentrically the shank 22 of a handle 23. This shank 22 extends outwardly from the casing 60 through an aperture in the cupboard provided for the same, to the front of the casing. At the point at which this shank passes through the casing, there is provided an annular flange 24 which bears against the 65 casing, and on this flange 24 is formed a knob 25. A suitable plate 26 is fastened by means of wood screws 27, to the face of the cupboard door, and at 28 there is an offset portion through which by means of the aperture 29, the handle member extends. This offset portion is adapted to hold the flange 24 slidably against the cupboard face. Pivoted to the knob 25 is a substantially U-shaped member 30. This member 30 is pref- 70 erably formed of resilient material, and its opposing arms are bent as at 31 to provide an eyelet 32 receivable upon a male snap-fastener 33. The lower end of this U-shaped member has formed thereon a suitable ring 75 34 by which it may be operated to turn the handle.

In actual operation my device operates in the following manner. When the cupboard door is in locked position, the U-shaped 80 member having engagement with the snap-fastener 33, does not permit rotation of the handle. The cupboard door is locked from without. In order to release the catch on the cupboard, the U-shaped member 30 is 85 swung outwardly so as to release its engagement with the snap-fastener, and the handle 33 is rotated to the left from the position shown in Figure 3, the cylindrical member 21, acting as a cam on the sides, and the elliptical aperture 18 moves the follower to the left and the bolt 15 being formed on the follower, is withdrawn into the casing and the cupboard door may be opened. Reversal of 90 this operation serves to project the bolt 15 100 so that the cupboard door may again be locked.

I do not desire to limit myself to the exact arrangement of parts shown and described. The specific design and workmanship is a matter of choice, and only in so far as I have pointed out my invention in the appended claims do I desire to be limited.

105 It will be understood that various changes in the detail of construction may be made 110

without departing from the spirit or scope of the invention as defined by the appended claims.

I claim:

- 5 1. A door catch comprising in combination a substantially rectangular casing, a rectangular follower slidably and loosely mounted in said casing, a substantially elliptical aperture extending through said follower, a cylindrical member eccentrically mounted in said casing, extending through said aperture, a bolt extending from said follower through said casing, a handle member keyed to said cylindrical member, serving as a shaft upon
- 10 15 which said cylindrical member is eccentrically mounted, said handle member extending exteriorly of said casing, a fastening member pivoted to said handle member so as to swing therefrom, there being a catch on said
- 15 20 fastening member and a stationary lug over

which said catch is adapted to be inserted to hold said handle stationary, whereby said follower will be fastened against movement.

2. A door catch comprising in combination a casing, a follower in said casing, a bolt on said follower adapted to project from said casing, cam means for moving said follower to throw or withdraw said bolt, a handle member for said cam means, said handle member extending exteriorly of said casing, a fastening member pivoted to said handle member so as to swing therefrom, and means cooperating with said fastening member to hold said handle stationary whereby said follower can be fastened against movement.

In testimony whereof I have signed my name to this specification.

BERT E. BARTHOLOMEW.
